Filed Aug. 22, 1958, Ser. No. 52,342

Term of patent 7 years

(Cl. D45—15)

FIG. 1

Fig. 1 is a front elevational view of a jewelry locket, showing my new design;

Fig. 2 is a right side elevational view thereof; and

Fig. 3 is an enlarged perspective view thereof with the locket in open position.

The oval configuration having a cover is the same at front and back, and is particularly shown, as to configuration, in Fig. 3.

I claim:

The ornamental design for a jewelry locket, as shown.
